Primary Examiner — Karen E Kearney*Assistant Examiner* — Katherine Holbrow(74) *Attorney, Agent, or Firm* — Ladas & Parry LLP(57) **CLAIM**

The ornamental design for a display screen or portion thereof with graphical user interface, as shown and described.

DESCRIPTION

The FIGURE is the front image for a display screen or portion thereof with graphical user interface showing our new design.

The broken lines showing the display screen and all other broken lines showing portions of the graphical user interface are included for the purpose of illustrating portions of the article and form no part of the claimed design.

1 Claim, 1 Drawing Sheet(56)
